UNITED STATES PATENT OFFICE

MARTIN T. HOOPER, OF ALHAMBRA, CALIFORNIA

VENTILATOR

Application filed November 2, 1928. Serial No. 316,756.

My present invention has reference to a stationary type of ventilator for buildings and my primary object is the construction and arrangement of ventilators for this purpose which will cause the air to sweep over the ventilator in a manner to exert a pulling action to create a vacuum in the said ventilator and thereby pull or draw foul air, smoke, vapors, etc., through the ventilator and out of the building.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

25 In the drawings:

Figure 1 is a sectional view of my improvement, approximately on the line 1—1 of Figure 2.

Figure 2 is a horizontal sectional view approximately on the line 2—2 of Figure 1.

In the showing of the drawings, I have illustrated my improvement supported upon the peak of a roof 1 of a building. On the roof 1 there is fixed the flanged edges of the hollow support 2 of the improvement. The support 2, of course, provides the transition piece between the building and the ventilator. The body pipe of the ventilator, indicated by the numeral 3, is fixedly secured to the rounded top of the transition piece 2, and riveted or otherwise effectively secured in the ventilator pipe 3 there are the offset ends 4 of upstanding or vertical supports 5. The supports are in the nature of metal plates and are spaced equidistantly from each other.

There is riveted, bolted or otherwise secured to the outer face of the ventilator, or there may be integrally formed with the outlet end thereof a downwardly inclined or flared wind deflector 6, the said deflector be-

ing provided at spaced intervals, on its outer edge with outwardly directed lugs or extensions 7 to which is secured a ring band 8. The hollow frusto conical or flared storm head of the ventilator is indicated by the numeral 9 and this storm head has its inner edges formed or connected with lugs or extensions 10 that merge into upwardly extending ends or flanges 11 to which latter there is secured a flat ring band 12 similar to the ring or band 8. It will be noted that the lower edge of the storm head is approximately in a line with the lower edge of the wind deflector 6. The braces 5 have their upper edges offset or formed with annular flanges which underlie the storm head and are riveted or otherwise fixed thereto, while also riveted or otherwise secured on the braces 5 there is a ring flange 21 of a downwardly and outwardly flared storm flange 13. The storm flange 13 it will be noted by reference to the drawings, is disposed between the wind deflector and the storm head.

Arranged for travel between the vertical braces 5 of the improvement there is an inwardly or downwardly flared damper member 14. This inverted hollow frusto conical damper member has secured thereto a flexible element 15 and this chain is guided around a sheave wheel 16 supported from the apex of the storm head. The chain is suitably guided over the damper and between the braces 5 and in the showing of the drawings, one end thereof is attached to a hook 17, whereby the damper may be arranged in its fully raised position, as disclosed by Figure 1 of the drawings or may be lowered to closed position on the top of the ventilator pipe 3 as also disclosed by the dotted lines in said Figure 1. Obviously, the damper may be positioned at any desired vertical adjustment with respect to the ventilator pipe 3.

The flat rings 8 and 12 have secured thereto the storm band of the improvement. This storm band is one of the important features of the invention, the same being made up of any desired number of arched plates 18, each of said plates being of the same width and length, the length of the said plates being greater than the distance between the outer

edge of the wind deflector 6 and the lower edge of the storm head 9. Each of the arched plates has a central portion fixed by means 19 to the rings 8 and 12. In the showing 5 of the drawings, each of the inwardly arched plates comprising the stationary storm band has one of its edges bent inwardly toward the improvement to provide a hook 20 that receives the free edge of the adjacent arched 10 plate therein. Obviously the lapping edges of the concaved plates may be suitably connected.

All of the parts constituting the improvement are fabricated in standard sections or 15 units for economy and ease in shipping, storing and erecting. The concaved plates or portions of the storm band, contacted by the wind provide what I will term the windward side of the improvement. These plates will 20 direct the wind away from the said windward side of the improvement. The wind deflector 6, at the windward side of the improvement will likewise deflect the currents of wind downwardly and outwardly with respect to 25 the improvement. The result is that the full force of air will be directed over the ventilator, so that a vacuum will be created in the ventilator pipe which literally pulls (and does not eject) foul air, smoke, etc., through 30 the ventilator and out of the building. Thus with my ventilator it will be seen that the storm band, incident to the height thereof and the positive low pressure air pulling area on the leeward side of the improvement (that is 35 is the side of the improvement opposite what I have termed the windward side) prevents wind blowing through the ventilator from the windward side. Also with my improvement the wind deflector and the storm flange 40 prevent outside air entering the ventilator head from the bottom of the improvement and the storm flange positively prevents storm elements entering the ventilator pipe. The draught through the ventilator, as previously inferred, is regulated by the adjustment 45 of the damper 14. It is to be further noted that all of the elements constituting the improvement are firmly and effectively braced.

50 Having described the invention, I claim:
1. A stationary type of ventilators for buildings, including a hollow support fixed on a building, a ventilator pipe fixed on the support, and said support affording a transition between the building and the ventilator pipe, upwardly extending spaced arms fixed on the ventilator pipe, a hollow frusto conical head fixed on the outer end of said arms, a downwardly flared storm flange surrounding and fixed on said arms, a downwardly inclined flared wind deflector surrounding and fixed to the mouth of the pipe, an inverted hollow frusto conical damper movable between the arms, a flexible pull element between the damper and the storm head for

adjusting the damper, a storm band surrounding the lower edge of the storm head and the wind deflector, fixed to these elements but spaced therefrom, and said storm band having equidistantly spaced vertically disposed concaved portions. 70

2. A stationary ventilator for buildings, comprising a hollow support, which is fixed on the roof of a building, a ventilator pipe fixed on the outer end of the support and said support providing a transition between the building and the ventilator pipe, upstanding arms secured to the ventilator pipe, an inverted frusto conical storm head receiving the upper ends of the arms therein and secured to said ends, said storm head having spaced extensions whose ends are flanged, a downwardly inclined outwardly flared storm flange fixed to the arms, a downwardly inclined outwardly flared wind deflector surrounding and fixed to the mouth of the ventilator pipe, said deflector having spaced extensions whose ends are flanged, flat rings secured to the flanges on the extensions of the storm head and wind deflector, a storm band arranged around the rings and fixed thereto, said storm band having its outer periphery formed with equidistantly spaced vertical depressions affording wind pockets, and a damper for the ventilator pipe movable vertically between the arms. 80 85 90

3. A storm band for ventilators of the class described, comprising vertically disposed plates all of the same length and width, and which plates are concaved inwardly and have their central portions fixedly supported, and the outer edge of each plate being inbent to provide a hook to receive the straight edge of the cooperating plate therein. 100

In testimony whereof I affix my signature: 105
MARTIN T. HOOPER.
